Title

UNITED STATES PATENT OFFICE.

JAKOB WOJCIECHOWSKI, OF WARSAW, RUSSIA, ASSIGNOR TO THE AMERICAN TOBACCO COMPANY, OF NEW YORK, N. Y., A CORPORATION OF NEW JERSEY.

CUTTING MECHANISM FOR CIGARETTES.

SPECIFICATION forming part of Letters Patent No. 732,330, dated June 30, 1903.

Application filed May 26, 1902. Serial No. 109,049. (No model.)

To all whom it may concern:

Be it known that I, JAKOB WOJCIECHOWSKI, a subject of the Emperor of Russia, residing at Warsaw, Russia, have invented certain new and useful Improvements in Cutting Mechanism for Cigarettes, fully described and represented in the following specification and the accompanying drawings, forming a part of the same.

10 This invention relates to certain improvements in cutting devices for cigarette-machines, and has for its object to produce a simple, cheap, and efficient construction by which cigarettes may be evenly trimmed.

15 With this and other objects in view the invention consists in certain constructions and in certain parts, improvements, and combinations, as will be hereinafter fully described and then pointed out in the claims hereunto 20 appended.

25 Referring to the drawings, which form a part of this specification, and in which like characters of reference indicate the same parts, Figure 1 is a plan view of the improved cutting mechanism, and Fig. 2 is a side view of the construction shown in Fig. 1.

30 Referring to the drawings, the cigarette-making mechanism may be of any suitable character, but in the construction hereinafter described is particularly designed for use with that class of cigarette-machines in which the cigarette is made by stuffing tobacco into a tube already formed and provided with a mouthpiece. Inasmuch, however, as the 35 mechanism by which the cigarettes are made has no particular relation to the present invention, it is not illustrated.

30 The cigarettes as they issue from the machine are advanced by cigarette-forwarding devices, which may be of any suitable description. As shown, the cigarettes drop from the cigarette-forming mechanism (not shown) upon a belt 160, which is or may be provided with a series of small projections, 45 which assist in moving the cigarettes along. As shown, these projections consist of beads 181, which are secured to a string 182, which is sewed to the belt, although they may be formed in any desired manner.

As the cigarettes are carried along by the 50 forwarding devices they are or may be given an endwise movement to even them up preparatory to cutting. The movement referred to may be given to the cigarettes by any desired mechanism. As shown, these devices 55 consist of a pusher, which is formed by a lever 183, which is pivoted at 184 to a bracket 185, rising from the bed-plate. This pusher operates upon one end of the cigarettes; but as it may happen that the cigarettes will not 60 fall uniformly upon the belt a second device may be provided, which operates upon the other end of the cigarettes. This device, as shown, consists of a pusher, which is formed by an angle-bar 186 on a lever 187, said lever being pivoted in a post 188, rising from one of a pair of extensions or frame-pieces 189, which are secured to the bed-plate or to the main frame of the machine.

65 The devices before described for producing 70 the endwise movement of the cigarettes may be operated in any suitable manner and either may be used without the other. Preferably, however, one of these devices will be operated directly, and when both devices are 75 used they will be connected to operate jointly. As shown, the lever 187 is provided with a depending projection 190, which is in the path of a slide (not shown) which travels in 80 ways 123, formed in the bed-plate. The movement of the lever in opposition to that produced by the slide is or may be effected by means of a suitable spring. As shown, a leaf-spring 192 is provided for this purpose, said spring being secured to one of the extensions 189 and operating against a projection 193, which is secured to the lever 187. A stop 194 is or may be employed to limit the 85 movement of the lever produced by the spring.

90 The belt 160 is shown as running over a drum, said drum being mounted on a shaft 195, which is journaled in the extensions 189, said shaft being driven in any suitable manner. A brush is or may be provided to clean 95 the belt, said brush being mounted on a shaft 196, which is supported in hangers 197, secured to the extensions 189. The brush is

shown as driven by a sprocket-chain 198, which runs over wheels on the shafts 195 and 196.

In addition to the belt the forwarding devices also preferably include a pair of narrow tapes 199, which, as shown, overlie the belt 160 and which serve to support and forward the cigarettes after they leave the belt. In the construction illustrated these tapes are shown as passing around a pulley 200, which is mounted on a shaft 201, located at the extreme forward end of the machine, said shaft being supported in bearings which are located in adjustable cheek-plates 202, suitably secured to the frame of the machine by nuts 203.

Means are preferably provided to act upon the cigarettes to straighten them, so that they will lie at right angles to their line of travel in order to be properly presented to the cutting devices to be hereinafter described. While the straightening means may be of any suitable character, as shown, a drum 204 is employed for this purpose, said drum being mounted on a shaft 205, which is suitably journaled in the side frames of the machine. The drum 204 is provided with a series of lifting projections, which are preferably in the form of blades 206. These blades preferably have their edges slightly curved, as shown, and lie between the pair of tapes 199, before referred to.

The shaft 205, which carries the drum 204, may be driven in any suitable manner. As shown, it is provided with a sprocket 207, which is driven by a chain 208, said chain being driven by a sprocket 209 on the shaft 195. As the cigarettes are forwarded by the tapes they are caught by the outer edges of the blades, and as they are lifted thereby they fall into the spaces between the blades, thus being positioned at right angles to the tapes. As the drum continues to rotate the cigarettes are again delivered by the blades to the tapes on the other side of the drum and are by them carried onward to the cutting devices.

The cutting devices employed may be varied in construction. Preferably, however, they will include a carrier 210, which, as shown, consists of a rotating drum provided with pockets 211. The drum is preferably constructed with circular channels or recesses 211', through which the tapes 199 pass, and is mounted on a shaft 212, suitably journaled in the side frame of the machine, this shaft being provided with sprocket-wheel 213, over which the chain 208 runs. A suitable tightening device 214 of ordinary construction is or may be provided to keep the chain taut. The cutter employed to coöperate with the carrier may be of any suitable construction. As shown, the cutter consists of a rotating knife 215, which is carried on a shaft 216, this shaft being supported by cone-screws 217, which pass through suitable brackets mounted on the side frame of the machine, said cone-screws enabling the shaft and cut-

ter to be adjusted to bring the cutter close to the edge of the drum, so that the tobacco which protrudes from the cigarette-wrapper is cleanly sheared off by the knife. This shaft 216 is provided with a pulley 218, over which runs a belt 219, said belt being driven from pulley 220, which is mounted on a shaft *m*. This shaft *m* is shown as slightly inclined and may be driven in any suitable manner from the mechanism of the cigarette-machine. Inasmuch, however, as the particular means for driving this shaft have no special relations to the present invention, the driving means have been omitted in the interest of clearness. The belt 219 is shown as running around a pair of direction-pulleys 222, which are mounted on a bracket 223, which extends from one of the extensions 189. This shaft 216 may, if desired, be provided with gearing by which the shaft 195 is driven. Inasmuch, however, as the particular means for driving this shaft 195 are not material to the present invention, the gearing referred to has been omitted from the illustration in the interest of clearness.

It is important that the cigarettes be accurately positioned in the carrier 210, so that the tobacco which protrudes from the paper will be cut off close to the edge of the paper; but the paper itself will be untouched by the knife. As it may happen that the cigarettes will be out of position longitudinally in either direction, shifting devices are preferably provided for acting on both ends of the cigarettes after they have been taken by the carrier. These devices may vary in construction. As shown, one of them consists of an angular plate 224, said plate forming a cam-surface against which the mouthpiece ends of the cigarettes may abut. This cam-plate 224 is carried on a horizontal pin 225, said pin being adjustable in one of the side frames of the machine and being locked in position by means of a set-screw 226 or in any other suitable manner.

The device for acting on the other end of the cigarettes, as shown, consists of a striker or shifter, which is formed by a bent spring-plate 227, said plate being mounted in a slotted pin 228, extending upward from the lever 187 and being held in position by means of a screw 229 or in any other suitable manner.

After the cigarettes have been operated upon by the knife they are again deposited on the tapes 199 and are by said tapes delivered to an endless carrier 230 or to any other suitable transporting device, by which they are carried out of the machine.

In order to prevent the cigarettes from jumping out of the pockets 211 in the carrier 210, holding devices are preferably provided which, as shown, consist of spring-plates 231, which are mounted on a rod 232, suitably supported in the frame of the machine. This rod is held in angular adjustment by means of a set-screw 233.

In order to keep the return run of the belt

160 tight, a belt-tightening device of ordinary form may be provided, said device consisting of a roller mounted in bearings 234, which are adjustable by means of screw 235.

5 While the construction which has been described embodies the preferred form of the invention, it is to be understood that variations and changes may be made therein without departing from the invention and that 10 certain features of the invention may be used independently of other features. The invention is not, therefore, to be confined to the specific details of construction hereinbefore described. While, furthermore, the invention 15 is particularly adapted for trimming cigarettes made by stuffing tobacco into tubes provided with mouthpieces, it may be used for trimming cigarettes made in other ways.

I claim—

20 1. The combination with cigarette-forwarding devices, of a cigarette-carrier, a knife operating therewith, and a straightening device which operates on the cigarettes before they are delivered to the carrier.

25 2. The combination with cigarette-forwarding devices, of a rotating cigarette-carrier provided with pockets, a knife operating with the carrier, and a straightening device which operates on the cigarettes before they are delivered to the carrier.

30 3. The combination with cigarette-forwarding devices, of a rotating carrier having pockets for the cigarettes, a knife coöperating with the carrier, and a rotating hub provided with 35 blades which operate to straighten the cigarettes before they are delivered to the carrier.

40 4. The combination with cigarette-forwarding devices, of a rotating carrier having pockets for the cigarettes, a rotating cutter coöperating with the carrier and a rotating hub provided with blades which straighten the cigarettes before they are delivered to the carrier.

45 5. The combination with cigarette-carrying tapes, of a straightening device having projections operating to lift the cigarettes from the tapes, whereby they become straightened.

50 6. The combination with cigarette-carrying tapes, of a rotating straightening device having projections operating to lift the cigarettes from the tapes, whereby they become straightened.

55 7. The combination with cigarette-carrying tapes, of a rotating lifting device provided with blades which operate to lift the cigarettes from the tapes.

60 8. In a cigarette-straightening device the combination with a rotating device provided with projections which lift and straighten the cigarettes of means for presenting cigarettes thereto.

65 9. In a cigarette-straightening device the combination with a rotating hub provided with lifting-blades, of means for presenting the cigarettes thereto.

10. The combination with cigarette-carrying tapes, of a straightening device provided

with lifting projections, said device working between the tapes and operating to lift the cigarettes therefrom and deliver them thereto 70 after the cigarettes are straightened.

11. The combination with a pair of carrying-tapes, of a straightening device provided with lifting-blades rotating between the tapes, said device operating to lift the cigarettes 75 from the tapes and deliver them thereto.

12. The combination with a pair of cigarette-carrying tapes, of a rotating hub located between the tapes and provided with lifting projections, and cutting devices. 80

13. The combination with cigarette-carrying tapes, of a rotating straightening device provided with lifting projections, said device being located between the tapes, a carrier also rotating between the tapes, and a cutter 85 coöperating with the carrier.

14. The combination with cigarette-carrying tapes, of a rotating straightening device provided with lifting projections, said device being located between the tapes, a carrier 90 also rotating between the tapes, and a rotating cutter coöperating with the carrier.

15. The combination with a pair of carrying-tapes of means for evening the cigarettes on the tapes, a straightening device, and cutting devices. 95

16. The combination with cigarette-carrying tapes of means for evening the cigarettes on the tapes, a straightening device, a carrier, a cigarette-shifting mechanism operating in 100 connection with the carrier, and a cutter.

17. The combination with cigarette-carrying tapes of means for evening the cigarettes on the tapes, a straightening device, a carrier, a cigarette-shifting mechanism operating in 105 connection with the carrier, and a rotating cutter.

18. The combination with cigarette-carrying tapes of means for evening the cigarettes on the tapes, a straightening device, a rotating carrier, a cigarette-shifting mechanism operating in connection with the carrier, and a rotating cutter. 110

19. The combination with a belt having forwarding projections, of tapes overlying the same, a rotating straightening device having lifting projections, a rotating carrier provided with pockets, a shifting mechanism coöperating with the carrier, and a cutter. 115

20. The combination with a belt having forwarding projections, of tapes overlying the same, a rotating straightening device having lifting projections, a rotating carrier provided with pockets, means for retaining the cigarettes in the pockets, a shifting mechanism 120 coöperating with the carrier, and a cutter.

21. The combination with cigarette-carrying tapes, of means for evening the cigarettes on the tapes, a rotating straightening device located between the tapes said device having 125 lifting projections, a rotating carrier located between the tapes said carrier having pockets, a shifting mechanism, means for retaining the cigarettes in the pockets, and a cutter. 130

22. The combination with a pair of cigarette-carrying tapes, of a pusher for evening the cigarettes, a rotating straightening device provided with lifting projections located between the tapes, and a cutting mechanism.
23. The combination with a belt having forwarding projections, of carrying-tapes overlying the belt, a pusher operating to even the cigarettes, a straightening device consisting of a rotating hub having lifting projections located between the tapes, and a cutting mechanism.
24. The combination with a belt having forwarding projections, of carrying-tapes overlying the belt, a pusher operating to even the cigarettes, a straightening device consisting of a rotating hub having lifting projections located between the tapes, a rotating carrier having pockets, and a cutter.
25. The combination with a belt having forwarding projections, of carrying-tapes overlying the belt, a pusher operating to even the cigarettes, a straightening device consisting of a rotating hub having lifting projections located between the tapes, a rotating carrier having pockets, a shifting mechanism, means for retaining the cigarettes in the pockets, and a cutter.
26. The combination with a belt having forwarding projections, of carrying-tapes overlying the belt, a pusher operating to even the cigarettes, a straightening device consisting of a rotating hub having lifting projections located between the tapes, a rotating carrier having pockets, a shifting mechanism, means for retaining the cigarettes in the pockets, and a rotating cutter.
27. The combination with a pair of carrying-tapes of a rotating straightening device having lifting projections located between the tapes, a rotating carrier having pockets, a cam operating to shift the cigarettes in the pockets, and a cutter.
28. The combination with a rotating carrier provided with pockets, of a cam located at one end of the pockets, a vibrating shifter located at the other end of the pockets, and a cutter.
29. The combination with a rotating carrier provided with pockets, of a cam located at one end of the pockets, a vibrating shifter located at the other end of the pockets, and a rotating cutter.
30. The combination with cigarette-carrying tapes, of a rotating straightening device having lifting projections located between the tapes, a carrier having pockets also located between the tapes, a cam at one end of the pockets for acting on one end of the cigarettes, a vibrating shifter located at the other end of the pockets for operating on the other end of the cigarettes, and a cutter.
31. The combination with a belt having forwarding projections, of tapes overlying the same, a pusher, a rotating straightening device having lifting projections lying between the tapes, a carrier having pockets, a cam located at one end of the pockets, for operating on one end of the cigarettes, a vibrating pusher located at the other end of the pockets for operating on the other end of the cigarettes, and a cutter.
32. The combination with a belt having forwarding projections, of tapes overlying the same, a pusher, a rotating straightening device having lifting projections lying between the tapes, a carrier having pockets, a cam located at one end of the pockets for operating on one end of the cigarettes, a vibrating shifter located at the other end of the pockets for operating on the other end of the cigarettes, and a rotating cutter.
33. The combination with a belt, of a pair of tapes overlying the same, a pair of pushers one on each side of the belt for operating on the cigarettes, a rotating straightening device having lifting-blades lying between the tapes, a carrier having pockets, a cam located at one end of the pockets for operating on one end of the cigarettes, a vibrating pusher located at the other end of the pockets for operating on the other end of the cigarettes, and a cutter.
34. The combination with a belt, of a pair of tapes overlying the same, a pair of pushers one on each side of the belt for operating on the cigarettes, a rotating straightening device having lifting-blades lying between the tapes, a carrier having pockets, a cam located at one end of the pockets for operating on one end of the cigarettes, a vibrating pusher located at the other end of the pockets for operating on the other end of the cigarettes, and a rotating cutter.
